CLAIM

The ornamental design for a gardening scraper head, as shown and described.

DESCRIPTION

FIG. 1 is a perspective view showing a gardening scraper head embodying the design, from the top and left;

FIG. 2 is a perspective view thereof, from the top and left;

FIG. 3 is an exploded perspective view thereof from the top and right side;

FIG. 4 is an exploded perspective view thereof from the top and left side;

FIG. 5 is a reduced scale top plan view thereof;

FIG. 6 is a right side elevation thereof;

FIG. 7 is a bottom plan view thereof;

FIG. 8 is a perspective view thereof, from the right side and front; and,

FIG. 9 is a perspective view thereof, from the left side and front.

The claim design is shown broken away to indicate indeterminate length.
